UNITED STATES PATENT OFFICE.

GLENN H. CURTISS, OF HAMMONDSPORT, NEW YORK, ASSIGNOR TO THE CURTISS MOTOR COMPANY, OF HAMMONDSPORT, NEW YORK, A CORPORATION OF NEW YORK.

METHOD AND SYSTEM FOR OPERATING RUDDERS OF AIRCRAFT.

1,228,380.

Specification of Letters Patent. Patented May 29, 1917.

Application filed February 18, 1914. Serial No. 819,521.

To all whom it may concern:

Be it known that I, GLENN H. CURTISS, a citizen of the United States, residing at Hammondsport, county of Steuben, State of New York, have invented certain new and useful Improvements in Methods and Systems for Operating Rudders of Aircraft, of which the following is a specification, reference being had therein to the accompanying drawing.

My invention relates to a rudder system particularly adapted for use in connection with the ailerons commonly used in several types of aeroplanes, and is as well adapted 15 for use in connection with warping ailerons as it is with hinged ailerons. As will be apparent however upon a full understanding of my invention, the same is applicable with advantage to any type of air craft 20 steered or balanced by any type rudder.

The prime object of my invention is to reduce to a minimum the power required to operate a rudder against wind pressure, and according to my invention I make use of 25 a new method which I claim herein as well as the apparatus. This method consists in utilizing the wind pressure acting upon the rudder when deflected to store up energy, and subsequently using said energy 30 to assist in the succeeding deflection of the rudder. The resulting ease of manipulation is of especial advantage in the case of unbalanced rudders.

Speaking more specifically in the terms 35 of the apparatus, my invention comprises a rudder, a relatively fixed support to which said rudder is attached, and a tension device interconnecting said rudder and said support at points removed from the line of 40 attachment of said rudder to said support, and normally exerting tension on a line intersecting the line of attachment of said rudder and support, whereby normally said tension device does not bias said rudder in 45 one direction or the other, but when said rudder is deflected, the line of tension of said member is also deflected and shortened and said tension device draws said rudder against wind pressure acting thereon in a 50 degree approximately inversely proportional to the angle of deflection of the rudder.

In the accompanying drawings I show the best forms of apparatus for carrying

out the method of my invention now known to me.

55

Figure 1 is an end elevation of the supporting surface of an aeroplane equipped with my invention,

60

Fig. 2 is a perspective view of one wing of said aeroplane,

65

Fig. 3 is a partial view similar to Fig. 1 of a modification, and

70

Fig. 4 is a similar view of a second modification.

75

Connected with the supporting surface 10 of Fig. 1 and Fig. 2 is an aileron 11. This aileron 11 is of rigid construction and is connected with the surface 10 by means of hinged joint 12, but the joint 12 may be of a rigid nature and the aileron 11 a flexible device which may be warped as well understood in the art. The characteristic of the aileron is that it normally trails in the wind, there being no appreciable wind pressure exerted on one side or the other 80 thereof. This aileron is operated up or down by means of operating cords 13 extending from suitable control levers (not shown) over pulleys 14 and struts 15 connected rigidly with the aileron 11, and at 85 their ends connected with the aileron at points removed from the line 12 of attachment to the surface 10. When deflected from its normal position by the operator, as for instance to the position shown in 90 dotted lines, the wind pressure thereon is a very considerable force, and sufficient to tire the operator in a very short time in case his machine is a large one and the wind variable. In a number of machines this is 95 overcome by mounting the aileron on an axis passing transversely through its mean center of pressure, or by attaching auxiliary surfaces directly or indirectly thereto. These expedients however cannot be readily resorted to in cases where the aileron is attached directly to one of the planes as in the Farman type. The method of my invention is applicable under all conditions at present known to me.

100

I interconnect the aileron 11 with the supporting surface 10 by means of transverse upper and lower spiral springs 16 and 16' which extend between points 17-18 on the aileron and supporting surface respectively, which points are removed from the 105

line of connection 12 of the aileron with the supporting surface 10. These springs are so connected that they, when the aileron is in its normal position, lie substantially flatly against or closely adjacent to the surfaces which they interconnect, thereby substantially intersecting by their lines of tension the line of interconnection 12 between the aileron 11 and the supporting surface 10. In this position the springs are under considerable tension which may be adjusted as desired to the proper degree. As shown in Fig. 2 there are preferably two sets of the springs 16—16', one near each lateral extremity of the aileron 11. When the aileron is deflected downwardly by drawing upon the lower operating cable 13, the upper spring 16 being bendable, bends around the hinge joint 12 without substantial increase in its tension and without substantial alteration of its effect upon the aileron 11, but the lower spring 16' is freed from the under surfaces of the members 10 and 11 and its line of tension is removed from the line of connection 12 between the aileron 11 and surface 10, whereby the lower spring 16' assists (to a degree depending upon its adjusted tension and inversely proportional to the angle of deflection of the aileron 11) in holding the aileron deflected against wind pressure. Under these conditions the spring 16' contracts, giving out the energy stored within it. The burden upon the operator may by these means be made as small as desired. When the aileron is returned to its normal position, the wind pressure assists the operator and energy is stored up in spring 16', the amount of such energy being a maximum when the spring reaches its full line position with the aileron 11 normal. On a succeeding downward deflection of aileron 11, this stored up energy is given out. The action of the upper spring 16 when the aileron is upwardly deflected is in all respects similar to the action of the lower spring 16', the lower spring 16' in this instance bending at the hinge joint 12 in the same manner as illustrated for the upper spring in the case described. I have found in actual practice of this invention that every advantage recited is actually attained in its use.

The modification of Fig. 3 consists in shortening the springs 16—16', and connecting them at one end with the aileron 11 by means of links 19—19' having pivotal connections 20 with the springs which lie closely adjacent the line of connection 12 between the aileron 11 and the surface 10. These links 19—19' may be rigid or flexible as desired.

The modification of Fig. 4 consists in the utilization of a single tension device 21 in the form of a compression spring held by a plunger 22 and a casing 23, connected re-

spectively to surface 10 and aileron 11. In this modification the line of tension instead of passing approximately through the line of interconnection 12 passes exactly through it, the tension device 21 being located either across the ends of the members 10 and 11 or in suitably disposed slots which may be provided as indicated in Fig. 2 in dotted lines. 70

While I have shown and described the best forms of my invention now known to me, I 75 desire to have it understood that many forms may be given my invention without departing in any wise from its generic spirit, and I desire to cover in the annexed claims all such modifications. 80

What I claim is:

1. In an aircraft, a rudder system comprising a rudder, a relatively fixed support to which said rudder is connected, and a transversely extending tension device on each side of said rudder interconnecting the rudder and its support, said tension device comprising a spring and a link respectively pivoted one to the other at a point adjacent the attachment of said rudder to said support. 90

2. In an aircraft, a rudder system comprising a rudder, a relatively fixed support to which said rudder is attached and a transversely extending tension device on each side 95 of said rudder interconnecting the rudder and its support, said tension device comprising a spring hinged at a point adjacent the line of attachment of said rudder and said support. 100

3. In an aircraft, a rudder system comprising a rudder, a relatively fixed support to which said rudder is connected, said rudder being when deflected biased to a normal position by wind pressure, and a transversely extending bendable tension member on each side of said rudder interconnecting the rudder and its support and normally exerting tension on lines passing close to the line of connection between said rudder and its support, each member being bendable about said line without substantial alteration of the force exerted on said rudder when the rudder is moved in a prescribed direction, and each on the other hand when the rudder is deflected in the opposite direction occupying a position removed from said line of connection and exerting a force biasing said rudder against wind pressure. 110 115

4. In an aircraft, a rudder system comprising a rudder, a relatively fixed support to which said rudder is connected, said rudder being when deflected in either direction biased to a normal position by wind pressure, and a transversely extending tension device on each side of said rudder interconnecting the rudder and its support, the tension of said devices while the rudder is in normal position being equilibrated whereby the rudder is not appreciably biased from 120 125 130

normal position, but when said rudder is moved in either direction from normal the equilibrium of tension being destroyed and a draft applied to the rudder by preponderating tension of one device or the other in the direction in which it has been moved.

5. In an aircraft, a rudder system comprising a rudder, a relatively fixed support to which said rudder is attached, and a 10 transversely extending tension device on one side of said rudder interconnecting the rudder and its support, said tension device comprising a spring having a hinge joint adjacent the line of attachment of said rudder and said support to permit deflection of 15 said rudder from its normal position.

In testimony whereof I affix my signature in presence of two witnesses.

GLENN H. CURTISS.
